DESIGN FOR A FLOWER STAND

Frank F. Solak, Klamath Falls, Oreg.

Application November 17, 1947, Serial No. 142,580

Term of patent 14 years

(Cl. D35—3)

To all whom it may concern:

Be it known that I, Frank F. Solak, a citizen of the United States, residing at Klamath Falls, in the county of Klamath and State of Oregon, have invented a new, original, and ornamental Design for a Flower Stand, of which the following is a specification, reference being had to the accompanying drawing, forming part thereof.

The figure is a perspective view of a flower stand, showing my new design.

I claim:

The ornamental design for a flower stand, as shown.

FRANK F. SOLAK.
